Primary Examiner — George D. Kirschbaum(74) *Attorney, Agent, or Firm* — Brian D. Kaul; Westman, Champlin & Koehler, P.A.(57) **CLAIM**

The ornamental design for an air-assist flare, as shown and described.

DESCRIPTION

FIG. 1 is a perspective view of the air-assist flare;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing is included for the purpose of illustrating portions of the "article" and forms no part of the claimed design.

1 Claim, 6 Drawing Sheets(56)
